(57) **CLAIM**

The ornamental design for a compact gun cabinet, as shown and described.

DESCRIPTION

FIG. 1 is a rear perspective view of our new compact gun cabinet according to the present invention;

FIG. 2 is a front perspective view of the present invention;

FIG. 3 is a top view of the present invention;

FIG. 4 is a front elevation view of the present invention;

FIG. 5 is a bottom view of the present invention;

FIG. 6 is a right elevation view of the present invention;

FIG. 7 is a rear elevation view of the present invention; and,

FIG. 8 is a left elevation view of the present invention.

The broken lines showing one or more gun barrels extending from the compact gun cabinet in FIGS. 1, 2, 4 and 6-8 are for illustrative purposes and form no part of the claimed design.
